UNITED STATES PATENT OFFICE.

FRANK RAINER, OF JERSEY CITY, NEW JERSEY, ASSIGNOR TO HUDSON WILLOW & REED FURNITURE FACTORY, OF JERSEY CITY, NEW JERSEY, A FIRM COMPOSED OF FRANK RAINER AND WILLIAM F. RAINER.

WILLOW CHAIR.

Application filed April 8, 1924. Serial No. 704,920.

To all whom it may concern:

Be it known that I, FRANK RAINER, a citizen of the United States, residing at Jersey City, in the county of Hudson and State of New Jersey, have invented certain new and useful Improvements in Willow Chairs, of which the following is a specification.

This invention relates to the manufacture of woven willow chairs and it consists in certain improvements directed especially to the manner in which the woven willow apron is formed and associated with that part of the frame of the chair which is below the seat and particularly the legs of the chair, the objects being to simplify and reduce the cost of the work of forming this part of the chair, increase the strength and durability thereof and improve its appearance and avoid the exposure of projecting ends of the willow at the exterior of the apron where it is likely otherwise to catch in the clothing of the occupant of the chair.

In the drawings, Fig. 1 is an outside elevation of a fragment of that portion of the apron of the chair which is at the front;

Fig. 2 is a sectional view of the chair in a horizontal plane above the apron, showing the top willow course;

Fig. 3 is a sectional view, also in a horizontal plane, showing the second or intermediate willow course; and

Fig. 4 is a fragmentary underneath plan of the apron, showing the lowest or third willow course.

Only that part of the chair frame which includes the four legs A is shown, it being understood that they will be surmounted by a suitable frame for the seat and thereby and if desired otherwise connected and braced.

The top mesh, marked B, of the woven willow apron may be formed in any way; my invention is not concerned therewith and so I have not shown the particular weave of the apron as to this part except as to the members C and D which all stand upright in the apron and are as follows: These members are all formed of willow, those marked C being short lengths terminating at their upper and lower ends in the top mesh B and lower mesh E (to be described)

and those marked D extending through the meshes B and E and embodied in the mesh E as will appear. All the members of the set C and of the set D are spaced from each other at regular intervals, the set marked C being inclined from left to right and those marked D from right to left and those of one set crossing the other. Some or all of the set marked D may have their upper ends extended into the weaves which will form the seat or the arms and back of the chair, as is frequently done, but this is not material and so is not shown. It will be noted that in the mesh E each member C stands close to a member D.

To impart the proper strength and also a desirable appearance to the mesh E which forms a border or band at the base of the apron it is desired in these constructions to form the upper and lower edges of this band thicker and more substantial in appearance than the intermediate portion. It is also desirable that notwithstanding the tapering form of the willow material the thickness of each of these edges as well as the said intermediate portion should be kept as uniform as possible throughout the front and two sides of the apron. It is also important that the lower mesh E of the apron should be strong and durable because of the strain that frequently comes upon it in moving the chair about. Again it is a serious fault in the apron if the ends of the willow project at the outside so as to catch in the clothing of the occupant. In view of these considerations I form the lower mesh E as follows:

The mesh E is composed of a top and a bottom course and an intermediate course, shown respectively by Figures 2, 4 and 3.

To form the top course (Fig. 2) I anchor the butt end portion of a strand *a* of heavy willow to one back leg A by bending the same near said end around the leg and, having passed its butt end *a'* inward of two adjoining members C D and then out between this pair and the next pair of members C D (all at the back) as shown in Figure 2, twine the strand inward and outward of the pairs C D at the back and then, passing the other back leg A, continue this twining process forward along one side, passing a front leg, and then, continuing this twin-

ing, passing the other front leg, and finally leave the free end of the strand to terminate between the latter leg and the back leg to which the strand was anchored. With this strand is intertwined in the same manner with the members C D another strand whose end b' projects inward between the first two pairs of members C D, said strand b being extended around the back, side and front of the apron the same as the first strand and having its free end b^2 terminating near that of the first strand, the strand b crossing the strand a where they extend between the pairs of members C D and passing each leg A on the side thereof opposite to that passed by the strand a . At a point before the pieces a and b pass the first front leg mentioned the "relay" pieces d and e enter the top course, their ends d' e' being turned inwardly; and they being intertwined with each other and the pairs of members C D and passing the legs A all the same as the pieces a b , terminating at the back of the chair with their ends d^2 e^2 turned inwardly; but in this case the butts or thicker ends of these pieces are their ends d' d^2 so that, as explained, the thickness of the course at the front and two sides will be practically uniform and only at the back, for the short extent where the butts overlap, will it be otherwise.

To form the intermediate course (Fig. 3) I use light willow strands. Starting at one side of the chair and about the middle of said side the ends f' g' h' of three strands f g h are projected inwardly through the successive spaces between successive pairs of members C D and carried to the rear, across the back and forward into the opposite side, having their other ends f^2 g^2 and h^2 inserted inwardly through the successive spaces between successive pairs of the members C D; other strands j k and l are treated in the same way as the strands f g h excepting that they are carried to the front, across the front and forward into the side opposite to that where they start, their ends j' k' l' and j^2 k^2 l^2 being turned inward. All these strands are intertwined with the pairs of members C D, but instead of each strand entering the successive spaces between the pairs of members each preferably passes two or more of the spaces at the outside but after entering one space pass out again through the next space.

The bottom course is formed as follows: Each member D (Figs. 1 and 4) has sufficient length so that when it is bent at the bottom of the apron to form an acute angle or in the present case to the left (Fig. 1) it will extend past several of the pairs of members C D, as five of these. The bent off portion of each such member D is designated D'. These portions are intertwined with each other and pass alternately in and out

through the spaces between the pairs C D, their ends all projecting inwardly as shown in the underneath plan (Fig. 4). The members C are kept from falling down out of place by resting at their lower ends on the bottom course, which is entirely formed by the extensions D' of the members D.

The described top course at the lower part of the apron is the main binding course, and it greatly strengthens the apron and reinforces at the point where it would otherwise be weakest—at the back of the chair—to arrange the pieces a b to extend one way and the strands d e the other way to complete the circuit of the apron, especially if the butts or thicker and stiffer parts of these two sets of strands are at the back.

As to the intermediate course, the usual arrangement is to insert the strands, in starting to intertwine, each into the successive spaces between the members C D until the circuit of the apron is completed; since by this arrangement the ends of the strands are left distributed throughout the whole circuit of the apron the work is not certain of being performed properly on account of some of the ends being in the vicinity of the legs. By arranging some strands, as f g h , at the back with their ends projecting forward and some strands, as j k l , at the front with their ends projecting rearwardly, and arranging the ends of these two sets to overlap at the sides of the chair intermediate the legs, this difficulty is avoided.

So far as I am aware it is new in this art as to the third or bottom course, which is composed of the bent-off ends of the members D, to arrange the ends of their bent-off portions so that after said portions have been twisted around each other as described each end will project inwardly. This avoids the presence of a ragged edge at the bottom of the apron usually produced by leaving the said ends projecting outwardly so that they are likely to catch on the clothing of the occupant.

Having thus fully described my invention, what I claim as new and desire to secure by Letters Patent is:

1. In combination, with a chair frame having four legs, a woven apron connecting the legs circuitously and including upright spaced members arranged between each two adjoining legs and flexible tapering strands arranged horizontally and each twined throughout its length about said members successively and all intertwined with each other, the strands being arranged in two sets with the butt ends of each set at the back of the chair and the other and thinner ends extended forwardly, those of one set in one direction and those of the other set in the opposite direction.

2. In combination, with a chair frame having four legs, a woven apron connecting the

legs circuitously and including upright spaced members arranged between each two adjoining legs and flexible strands arranged horizontally and each twined throughout its 5 length about said members successively and all intertwined with each other, the strands being arranged in two sets, one at the back

of the chair and having their ends projecting forwardly and the other at the front of the chair and having their ends projecting 10 rearwardly, the ends of the forward set overlapping those of the rearward set.

In testimony whereof I affix my signature.

FRANK RAINER.
